UNITED STATES PATENT OFFICE.

WILLIAM F. ZIMMERMANN, OF MAPLEWOOD, NEW JERSEY, ASSIGNOR TO GOULD & EBERHARDT, OF NEWARK, NEW JERSEY, A CORPORATION OF NEW JERSEY.

FIXED-ANGLE HELICAL-GEAR HOBBER.

Application filed January 23, 1925. Serial No. 4,207.

This invention is devoted to machines accommodating hobs of different pitches and adjustable for hobbing helical (as distinguished from spur) gears in various sizes and of various numbers of teeth and conforming to a predetermined base or helix angle of substantial magnitude, say about an eighth to a third of a quadrant; the fundamental objective being to reconcile certain incompatible factors so as to provide a structure of maximum rigidity, cutting-ability and accuracy, of minimum complexity and cost, and yet sufficiently adaptable when installed to produce a range of gears satisfying all ordinary shop requirements. This objective, has been attained, in part through certain improvements over and reorganizations of the mechanisms disclosed as well in my United States Patent No. 1,472,767, as in my pending applications Serial No. 720,393, filed June 16, 1924, and No. 734,487 filed August 27, 1924, and in part, by resorting to certain novel conceptions and characteristic combinations; all as set forth herein-after.

For example, my Patent No. 1,472,767 illustrates a machine primarily suitable for cutting spur-gears of a single pitch and limited range of numbers of teeth, but in that machine the work-support is shiftable and the mounting of the cutter spindle is incompatible with the use of compound change-gears for extending the range unless the balanced drive be sacrificed. In my application No. 720,393, there is shown a machine for cutting spur-gears of different pitches and a wider range of numbers of teeth, but again the work-support is made shiftable and the cutter spindle does not conform to my present invention in respect to providing a plus and minus incremental adjustment from a substantial base-angle and furthermore the relation of splined to un-splined shafts is different. In my application No. 734,487, the machine illustrated presents the structural advantage of a non-shiftable work-support but, while it is primarily suitable for cutting spur-gears within the range of my aforesaid patent, it neither shows a combination which is simplified and yet is adjustable to accommodate various conventional hobs nor does it show one compatible with a drive which is balanced and yet including compound change-gears for correlating the ratios to yield the helical effect;

all of which would be essential in a machine satisfying the need for the present invention with its attendant special advantages.

What is meant by "balanced drive" by "base-angle" and by "incidental angle", as used herein may be defined as follows: A "balanced drive" denotes a special relationship between the elements connecting the driven cutter spindle and the driven work spindle respectively with the common source of power; said relationship being such that neither branch presents more sources of back-lash, such as pairs of intermeshing gear-teeth, than the other branch; thereby reducing disproportions in vibrations and minimizing the tendency to chatter under the intermittent releases of successive teeth from the work. A "base angle" signifies the helical angle of the teeth at the pitch line of a fixed magnitude with respect to the axis of the helical gear the machine is correlated to produce, and by "incidental angle" is meant the requisite departure from the base angle to compensate for the helical angle of the hob cutter and its magnitude is dependent upon the pitch diameter and number of threads of the cutter.

In any machine, and especially in one for hobbing helical gears involving the mechanical problems existing where there is an intricate correlation of component motions, each reduction in the number of individual parts contributes proportionally both to the sturdiness and to the intrinsic accuracy of the machine, and these qualities are of paramount importance where helical gears are to be accurately generated by a hobbing effect; all of which is fully realized by those skilled in this special art.

The general objective of this invention is to accomplish a reorganization of a helical-gear hobber such that its stationary (as well as its moving) elements will not only be reduced in number to the minimum, but will be arranged in efficient mutual relations; all in such a manner that the machine will still exhibit the capacity needed by its users in order to meet the actual range of operations demanded by the more prevalent conditions of shop usage. Considering the ultimate or terminal elements for driving the hob, for instance, their number should be as few and their action should be as direct as possible, and yet they should provide adjustments (in the angularity of the setting of the hob)

such that different short hobs may be interchangeably employed and helical gears of different pitches may be cut; it being important in all such angular adjustments to maintain a proper relation between the hob and the work-axis such that the hob will not be displaced unduly to one side or the other and so that the full generating action of the hob will be utilized in completing the proper contour of the tooth.

By so devising the hobber that it, in a structural sense, resolves the complete working-angle into a comparatively large base-angle (related primarily to the helical gear) and into a comparatively small incidental angle (related primarily to the hob) it becomes possible to achieve a simplification heretofore unknown in machines employing short hobs for generating helical gears. That is to say, by thus differentiating, it becomes feasible to discard the rather involved and round-about drive heretofore necessitated in single-hob machines where the center of swing of the hob was at or near the intersection between the axial planes of the hob and the work respectively, and, in lieu thereof, to resort to a fundamentally simple and immediate drive in which the center of swing will be located, not at said intersection or midway the slideway, but at one end of the hob-spindle; the extent of the swing in the new arrangement not being sufficient, in the absence of a re-mounting of the hob, to yield a choice of materially different base angles but being nevertheless adequate to accommodate all of such minor angles as may be incidental to a substantial base angle of predetermined magnitude. This mechanical premise of adhering to what may be regarded as a fixed base angle and providing latitude with respect to what may be regarded as an incidental angle, opens the way in generating helical-gears to the use, directly on the end of the hob-spindle, of an angle gear in a dual capacity, i. e., as a swivel-gear as well as a driving-gear: its mate being on (and its center of swivel being coaxial with) an off-set short cross-shaft geared directly to a main transmission shaft. While such an arrangement would not (in the absence of troublesome manipulations or structural complications) yield a range of swing sufficient to enable the machine to be adjustable to cut other than helical teeth by reason of the resultant displacement of the short hob (the shift being proportional to the disproportionately-varying cosine of the angle of variation) it will nevertheless afford as much adjustment as may be required for the incidental angle to compensate for the different helix angles of conventional hobs and it will accordingly permit the cutting of helical gears of different pitches with the same base angle of helix, and it will also accommodate the employ-

ment of simple or double thread hobs; all through a drive of fundamental simplicity, of few parts, and characterized by directness of action. It is to be remembered, in this connection, that the length of a hob, which is a complex and costly tool, is limited by various considerations well known by those skilled in the art and that, as a consequence, hobs must be quite short in length and hence the region of the hob available for cutting purposes is confined rather closely to the middle of the hob, and further, that middle region must be kept quite near the intersection of the axial planes of the hob and of the blank so as to avoid any necessity for any considerable lateral resetting of the hob on the cutter-spindle. Therefore, in a machine organized under the principles stated, it will be sufficient (through the off-set center arrangements) to provide a range of swing of say about 10° and to locate that range at the region of inclination determined by the base angle; any extension of that range being surplusage in a machine devoted to the hobbing of helical gears and which attains the adjustment through the off-set location of the center of swing, and in which, through the directness of the drive and the fewness of the parts, there is secured the freedom from vibration and incipient chatter which is of such great consequence where helical gears are to be generated by the hobbing effect. It may here be noted, further, that this proposition renders it especially feasible to employ, as an improvement in detail, that species of swivel angle-gears known as a worm and worm-wheel with the resultant advantage that the drive will be steadier and helical gears of a smoother finish and of a contour conforming with greater precision to the ideal may be generated. Where the center of swing is not off-set in the manner herein proposed, i. e., where it is midway the ends of the spindle in the vicinity of the aforesaid intersection (as has heretofore been the practice in helical-gear hobbers) it is not feasible to employ or secure the special advantages of a worm-wheel drive at the cutter-spindle by reason of the complications of the conventional round about drive.

It furthermore is the aim of this invention to merge the above noted improved improvements with a balanced-drive system yielding the helical effect and to correlate that combination with a reorganization of the major frame-elements of the machine which will avoid the habitual intervention of a work-supporting carriage between the bed and the work-supporting spindle; this being accomplished by journaling that spindle directly in the bed of the machine near one end and so devising and mounting the stanchion that it may be shifted as herein-after explained to provide the adjustment

for various diameters of work. Among the advantages derived from the manner of mounting the spindle are (1st) by eliminating the carriage, the axis of the hob may be located closer to the slideways of the stanchion and the "overhang" is thus reduced and less vibration can occur in the hob; (2nd) the work-supporting spindle has a more solid support directly in the heavy casting of the bed and hence it exhibits to a pronounced extent the desirable characteristics of an anvil so that the work is supported thereby in a manner well adapted to receive, without manifesting vibration, the hammer-like blows of the successively acting teeth of the hob; (3rd) the work spindle is always located at the same place with respect to the end of the bed and thus is at all times equally within the easy reach of the attendant whether for cutting gears of larger or of small diameters; and (4th) the fixed position of the spindle on the bed enables a larger worm-wheel to be affixed to its spindle and enables the bed casting to be reinforced and made more rigid with the same weight of metal than if clearances for the travel of the enclosed worm-wheel had to be provided.

To take advantage of the otherwise necessary massiveness of the stanchion by utilizing it in a steadyng capacity is likewise within the objective of this invention. The stanchion, which is virtually a part of the bed, has to be provided as a support for the hob, and as the hob is necessarily located some distance from the plane of the bed, the stanchion must be large and, being large, it must be heavy and massive so that it may not flex or quiver under the action of the hob. Now, by making this rather ponderous element capable of being slid on the bed (through an agency such as will be described) it has the general characteristics of a shiftable anvil and is, by its very massiveness, capable of absorbing the shocks largely independently of any means for clamping it to the bed. Furthermore, its great weight tends to hold it firmly on the ways of the bed and that weight acts in the same direction as the clamping elements and hence the stanchion admits of being better and more rigidly secured to the bed by the same clamping force as a relatively thin carriage which naturally tends to deflect and thus localize the clamping pressures. Also being large, the stanchion provides a base of ample dimensions and those proportions are adequate for the needs of a slidale element and do not have to be enlarged; so that, by eliminating the carriage and thus reducing the number of major elements of the machine, a saving of the equivalent weight of metal may be accomplished and yet a more rigid construction attained. To slide the heavy stanchion, as will be perceived here-

inafter, this invention embodies a power traverse mechanism which enables the user to perform that labor without effort; means for accomplishing that initial movement by manual power being also available for finer adjustments.

Fig. 1 is a side elevation of a hobbing-machine showing a fixed work-spindle and a shiftable stanchion supporting a head slideable thereon which carries a hob-spindle mounted at a major angle and adjustable plus and minus therefrom through a minor incidental angle. Figs. 2 and 3 are rear and front end-elevations of the machine. Fig. 4 is a skeleton of the transmission system and control levers for performing the various movements of the working and positioning elements of the machine. Fig. 5 is a modification of the hob-mount. Fig. 6 is a sectional detail of a friction coupling between the prime-mover and a part of the transmission system. Fig. 7 is a side elevation in detail of a portion of the interlocking control system for the quick traverse and feed for the hob-carrying head. Fig. 8 is a condensed fragmentary side-elevation of the means actuated by the cutter-slide for automatically operating the manually-operable levers for controlling the feed and the quick-traverse. Fig. 9 is a detail of the spring snap clutch for throwing in and out the feed transmission. Fig. 10 is a detail of the spring-detent for urging the feed hand-lever into either one or the other of its alternative positions. Fig. 11 is an end-elevation of said levers. Fig. 12 is a sectional-elevation, through line 12-12 of Fig. 4 showing an interlock for enabling the user manually to swing the main control lever from its "stop" to its "start" position; and showing also spring-operated means combined with means for releasing said interlock to enable said spring-operated means to perform the operation of throwing said lever into its "stop" position.

The bed A, in this embodiment, is elongated and positioned horizontally and provides a forward working region in which the work-spindle is directly journaled so as to occupy a fixed position, and the bed provides also a rear mechanism supporting region on which the stanchion is slidably mounted. The work spindle W is shown journaled in fixed bearings A' and it extends downwardly into the interior of the bed as indicated by W' and, at its lower end, carries a worm-wheel W² by which it is driven. The portion of the bed that houses the worm-wheel W² is appropriately enlarged to contain that wheel, and inasmuch as the wheel occupies a fixed position in space, the bed admits of being ribbed and reinforced closely to the wheel and thus made very rigid as will be understood without illustration. It is noteworthy that by

thus giving the work spindle a fixed position at the forward end of the bed, it is at all times quickly accessible to the user and it is not at one time further from the end of the bed than at another as often happens when the work spindle is shiftable in position. The mounting of the spindle is accomplished in a very solid manner with the object of realizing the effect of an anvil so that it virtually supports the work substantially as solidly as though it was clamped to the bed itself and, in consequence, the tendency to vibrate and chatter is reduced to a minimum.

The stanchion S is in the nature of a heavy box-like casting which is provided with slideways S' and S^2 at right angles to one another; the slideways S' resting on the slideways S^2 provided by the surface of the bed and arranged to permit the heavy stanchion to be slid towards and away from the axis of the work spindle for the purpose of determining the diameter of the gear G to be cut by the machine. The purpose of the transverse slideways S^2 is to support and guide a head H which is thus shiftable in parallelism with the axis of the work-spindle so that the cutter or hob (which is carried by the head) may in the course of the feeding movement cut the teeth of the gear G . It will be understood that this head H is suitably gibbed to the slideways S^2 and, in order to counterbalance the weight of the head H , a counterweight H^4 may be arranged to rise and descend in an appropriate well provided by the stanchion S ; conventional ropes and pulleys H^2 and H^3 being provided as will be understood.

It is to be noted that the stanchion, being heavy and massive, is in effect a part of the solid bed itself because when clamped down to that bed, it becomes very solid therewith owing to the action of the clamps augmented by the weight of the stanchion and by reason of the fact that the base of the stanchion S is very extensive so as to resist effectively such overturning forces as result from the pressure of the hob against the work during the tooling operation. It will likewise be noted that the stanchion requires to be shifted only when a change is to be made in the diameter of the gears being cut which ordinarily would be quite infrequent and it will also be noted that the shifting of the stanchion does not reduce the facility of access of the user to the work spindle and does not interpose obstructions when brought closer to that spindle. It will also be noted that the slideways S' at the base of the stanchion run to a region substantially underlying the head H so that this construction avoids the objectionable overhang which is necessitated whenever the work spindle is mounted on a carriage which slides on the bed.

65 The transmission system for rotating both

the work spindle and the hob, and for progressively feeding the head H , and for shifting the position of the stanchion S , and for varying the rates of rotations and for shifting the parts quickly or slowly as the case may be, will now be described.

This transmission is in the nature of a balanced drive and comprehends an intermediate splined shaft X and two main transmission shafts Y and Z ; shaft Y being also splined. These two shafts are disposed at right angles and the intermediate shaft is parallel with one of them; the latter being in this embodiment the shaft that communicates motion to the work spindle. The intermediate shaft receives the power in the first instance; this being accomplished by the power line consisting of a pulley or other prime mover, a friction clutch the power shaft P' and appropriate gears such, for example, as the two spur gears P^2 and P^3 and the two angle gears P^4 and P^5 . The splined transmission shaft Y is journaled in the shiftable stanchion so as bodily to travel therewith and at its lower end is provided with an angle gear y which meshes with an angle gear x' which is splined to the intermediate shaft X .

The cutter C is mounted on a spindle c which is journaled in the head at a fixed major angle sloping either to the right as shown by Fig. 3 or to the left as shown by Fig. 4, but in order to provide for a slight plus and minus variation of that major angle, the journals of the hob-spindle have a slight adjustment on the head H ; as by means of bolts 100 and curved slots 101 struck about the axis 102 of a worm 103. The minor angle adjustment will be, plus and minus, in the neighborhood of five degrees for a single thread hob, and correspondingly greater for a multiple-thread hob.

The immediate drive comprises a worm-wheel 104, the worm 103 and a co-axial bevel 105, and a bevel 106 splined to the vertical transmission shaft Y ; giving the adjustable right-angled 4-gear-drive shown by the drawings.

The lower horizontal non-splined transmission shaft Z is journaled in the bed of the machine and has a worm z' affixed thereto for driving the work-spindle W through the worm-wheel W^2 . The two pairs of change gears x^2 and z^2 , and 107 and 108, establish the driving relation between the intermediate power shaft X and the transmission shaft Z ; it being observed that this arrangement provides a balanced drive in which the six gears W^2 , z' , z^2 , 108, 107 and x^2 transmit the motion to the work spindle, and likewise six gears 104, 103, 105, 106, y and x' transmit the motion to the cutter. Further details will be described in connection with an explanation of the manipulations of the machine.

The controls for the hobber, will now be explained. These provide for preliminary adjustments such as setting the hob at the required distance from the axis of the work to cut a helical-gear of the desired diameter, and also for readily getting the hob close to the end of the blank so that it will not have to travel far, after the whole correlated system is set and started in its fixed ratios of movements, before the hob comes into engagement with the blank and begins its cutting operation.

Once the actual tooling operation is in progress, no independent cessation, variation or reversal of any of the movements should be made for, so long as any part of the cutter is in the blank, any departure from the correlated ratios would mutilate the helical gear in process of formation. But occasion may arise for suspending the cutting operation and provision for this is accomplished through a control for expeditiously stopping or starting the entire system of movements without in any manner affecting the pre-determined correlation of ratios.

When the hob has run through the blank, and is entirely clear thereof, its travel must in due time be arrested; otherwise damage to the machine would result. The machine, at that particular time, may not be under the close observation of the user and, to safeguard it against accident, there is provided an automatic stop for discontinuing further travel of the cutter-head; but only after there is no possibility of any interference between the hob and the gear.

After the hob has completed its work, and after the finished helical gear has been removed from the work-spindle, it is desirable to return the hob to its starting point without undue loss of time, and a quick return control is provided for this purpose. The user may then insert a fresh blank and set the mechanism again in operation to repeat the cycle.

To manually shift the stanchion a hand-wheel V (provided with graduations or micrometer adjustments) is affixed to a shaft that carries an angle gear V' which meshes with an angle gear V^2 which in turn is splined to the screw S^2 which runs through the fixed nut N and causes the screw to translate bodily; this translation being communicated to the stanchion by means of an appropriate lug or part S^4 journaled to the screw. This manual means enables the user very readily to bring the stanchion to any desired position with respect to the work-spindle for cutting helical gears of predetermined diameters.

To start the machine the power lever B is actuated. This shifts the collar 8 and slides a long key 9 (which is translatable counter-sunk in the shaft P') and this key actuates

prime mover P and the shaft P' . The transmission elements previously described are then maintained in motion by the power, and the cutter and the work are both revolved and fed at the co-relative rates determined by the two change gears z^2 , 108, 107 and x^2 . A characteristic of the arrangement of this lever is that it is uni-directional in manipulation, i. e., it may be moved by hand to start the machine but, when so moved, it is held by a catch against being manually shifted back again, so that, to stop the machine, the starting lever must be released from the hook by means to be later referred to.

So much of the transmission system as constitutes the balanced drive for the two spindles has been described. The motion for feeding the hob is conveyed by a transmission consisting of an angle gear 1 mounted on the shaft Z and meshing with an angle gear 2 affixed to the shaft 3 . A worm 4 on that shaft drives a worm-wheel 5 which turns the shaft 6 and (through appropriate change-gears designated generally by 7) the gear r^2 is driven and this gear is affixed to a sleeve r which is loosely mounted on the shaft F^6 which conveys the motion for feeding the cutter-head. The clutch teeth r' are maintained in engagement so long as the hob is in the blank, but they may be disconnected to permit the shaft F^6 to be driven by other means when the hob is to be shifted down into proximity with the blank or shifted up past the removed blank into its initial position to start on the next cycle, as will be explained later.

Angle gears F^5 and F^4 transmit the motion of the shaft F^6 to the shaft F^3 which is journaled in the stanchion and, at its upper end, has a gear F^2 which meshes with a gear F' which is a unit with a nut that turns about the non-rotatable feed-screw F . That feed-screw is affixed to the head H and is caused to move up or down, as the case may be, by the rotating nut. In this manner, the hob journaled on the head H is caused to feed downwardly whenever the hob is in the blank and the parts are connected as described, or caused to make a quick traverse either up or down when the hob is clear of the blank and the parts are differently connected, as will be described.

To stop the entire machine, either manually or through an automatic trip, the hook 112 must be depressed. To do this manually, the lever 109 must be operated; said lever 109 serving to release the catch and enable the lever B to return and the master-clutch to open through a quick-acting spring action. Referring to Fig. 12, there will be seen an arm 110 extending from the pivot-shaft 111 of starting-lever B . The extremity of said arm 110 over-rides a depressible hook 112 (see also Fig. 4) which is keyed to a rock-shaft 113 extending along-side the

machine and splined to a bell-crank lever 114; the one arm 109 of which is operable manually, and the other arm 115 of which is operated automatically by certain trip mechanism:—in each case to stop the entire machine. A spring-pressed plunger 116 normally holds up the hook 112 but permits its depression as described. When thus depressed, the catch is released and the arm 109 becomes free to swing and the starting lever B can now move into its “stop” position; this being done by the pressure of a spring-pressed plunger 117 which acts against another arm 118 also extending from the pivot-shaft 111, with the result that the collar 8 is shifted on the main power shaft P' to open the master-clutch.

The transmission which is utilized to drive the shaft F⁶ at a quick-traverse rate (in lieu of the slow-driving gear r²) when it is desired to accomplish a preparatory shift of the hob-carrying head, is as follows: Fast to the pulley P is a gear Q which permanently meshes with a gear Q' which is frictionally connected through the leather facings 17 and 18 (see Fig. 6) of the clamp disks 19 and 20 with the shaft Q²; a nut 21 serving to determine the amount of the friction. In this manner, the shaft Q² is driven simultaneously with, but impositively by, the pulley P so that slippage may occur and breakage prevented in case the head be brought against some obstacle. On the end of the shaft Q² is a bevel gear Q³ which permanently meshes with right and left bevel gears Q⁴ and Q⁵ which are loosely mounted on the shaft F⁶. A clutch Q⁶ is splined to the shaft F⁶, and when shifted to the one side or the other, will cause that shaft to be rotated either one way or the other; or not at all if the clutch Q⁶ be in neutral position. The position of the clutch is determined by a finger e projecting from a lever on the rock-shaft d which, through the bevel gears e and e', is actuated by the rock-shaft b which in turn is rocked by the hand-lever a.

To shift quickly down the cutter head, the lever a must be moved down into the lower dotted position shown by Fig. 11. Before this can be done, the block pin g must be pulled against its spring out of the path of that lever. This temporary obstruction is precautionary so that the user will be obliged deliberately to perform an extra operation to bring the head down rapidly; otherwise he might inadvertently press down the lever a and cause the cutter to be brought down rapidly into the work and broken. From what has been said heretofore, it will be seen that this depression of the lever a connects the shaft F⁶ with a high speed transmission and, since that shaft must also be connected with a low-speed or “feed” transmission to produce the correlated ratios used whenever the hob is in the work, it is

essential that the one shall be out before the other can come in and conversely. This safeguarding is accomplished by the interlock shown by Fig. 11 in which the rock-shaft m that controls the connection (by shifting the gear r² of the slow motion transmission, has an arm k² provided with a V-shaped finger f which (when the feed is “on”) enters a central recess in the ledge a² of the lever a. When, however, the lever a is not in its neutral position, the finger f will, by reason of its double slope, be forced out of the recess and caused to ride on the higher portions of the ledge a² and this can only happen when the feed-lever k is in the dotted position indicated by Fig. 11.

The means whereby the rock-shaft m determines the engagement and dis-engagement of the clutch teeth r' is shown best by Figs. 4 and 9. A shifter arm p acts to bodily shift the sleeve r to establish or disconnect the parts described; this shifter arm being loosely mounted on the shaft o. A yieldable detent p' acts on the shifter pin so as to urge the parts into clutching relation; the purpose being to provide a quick yet not too positive an action. Bevel gears n and n' connect the shaft o with a rock-shaft m and a hand-lever k permits the rock-shaft m to be moved manually. On this rock-shaft m is a small arm m' which has a spring-pressed pawl 22 cooperating with an oscillatable pawl m². The latter, by moving against either the stop-pin 23 or the stop-pin 24, will resiliently determine the position of the rock-shaft m and this motion will be correspondingly imparted to the rock-shaft o, which carries the part p³ provided with the aforesaid yielding detent p' to throw the sleeve clutch r impositively into operative position and provided also with the lug p² to throw it positively out. Thus it will be seen that when clutch Q⁶ is in either its right or its left engaging position, clutch r' is disconnected, and when clutch r' is engaged, clutch Q⁶ can be only in its neutral non-transmitting position. Therefore, by pulling out pin g and by depressing the lever a, the feed is disconnected and the quick traverse is accomplished and the head H moves down rapidly.

To shift quickly and upwardly the cutter head, the lever a is raised to the upper dotted position shown by Fig. 11. The interlock again insures that the feed will be out so that when the clutch Q⁶ is moved into its motion reversing position, the transmission will take place through the quick traverse means and the head will go up rapidly.

To adjust the limits of the “quick traverse” travel of the cutter head, this invention provides a shift-rod T pivoted to the free end of an arm a' extending to the right (as shown by Fig. 11) from the pivot of the

hand-lever *a* so that, when lever *a* is depressed, the shift-rod *T* will rise, and conversely. Hence if said rod *T* be pushed down, the effect will be the same on the control mechanism as if the user had pulled up the hand-lever *a*.

Now, adjustably bolted (by slot 10 and bolts 11) to the cutter-head *H* is a cam-plate *D*. This has an inclined face 12 and within the path of travel of that face will be (when the quick down traverse is on) the finger 16 on the end of the lower arm of a bell-crank lever *E* which has a fixed pivot at 15. The shift-rod *T* is pivoted at its upper end 14 to the other arm of that bell-crank lever. Hence, when the shift-rod is raised (to produce a quick down-traverse) the finger 16 will be in the path of the cam-plate *D*. If now the cutter-head descends, the inclined face will in due time contact with the finger 16 and depress the shift-rod *T*; thus raising the hand-lever *a*.

But this automatic raising of the hand-lever *a* (corresponding to a depression of the shift rod *T*) will cease as soon as the inclined face 12 has passed the finger on the bell-crank lever *E*. It is to be noted that the extent of this movement is such that, when the finger is coincident with the flat non-sloping face 13 of the cam-plate *D*, the hand-lever *a* is in its mid-position as shown in full lines by Fig. 11. Hence the detent *f* of the feed hand-lever *k* will now be able (when actuated by the user) to enter the notch in the surface *a*² and the down-feed of the cutter-head will be substituted for the down quick-traverse. The cutter is now about to enter the work at a "feed" rate only and cut the gear-teeth. If now the user should try, through a mistake, to push down the hand-lever *a*, he would be prevented by the finger 16 which is now riding along the non-sloping face 13. Therefore, the down quick-traverse is limited (by adjusting the initial position of the cam-plate *D*) and the user cannot commit the error of causing the cutter to enter the work at any rate faster than that of the normal "feed."

To adjust the limit of the upward quick-traverse, the collar or dog *T*² is set at the appropriate point on the rod *T* so that the projection *H*' (affixed to the cutter-head) will engage said collar and move the traverse rod *T* upwardly and thereby depress the hand-lever *a* from its raised into its neutral position. This will stop the travel of the cutter-head *H* because the detent shown by Fig. 10 will hold the hand-lever *k* in the dotted line position shown by Fig. 11 until it is actuated by hand.

To limit the extent of feed, there is an adjustable collar 33 on the feed shift-rod 34 which controls the position of the hand-lever 109 as will be understood. Also, as a mat-

ter of precaution, collars *T*', 36 and 37 are permanently affixed to the respective rods *T* and 34 to prevent the user from making any adjustments beyond the maximum scope of travel provided for the cutter head *H*. 70

The shift-rod 34, being pivoted to the arm 115, will turn the shaft 113 counter-clockwise, as viewed by Fig. 12, whenever the projection *H*' on the descending head *H* meets and pushes down the collar 33. This 75 will release the catch 112 and permit the spring-plunger 117 to snap open the master clutch in the main pulley *P* and thus stop the entire machine: excepting of course the auxiliary quick-traverse line from *Q* to the reverse gears *Q*⁴ and *Q*⁵ which idle with the prime-mover *P*. The user will, of course, so adjust the collar 33 on the shift-rod 34 that the hob will have fed entirely clear of the blank before the correlated drive-system is 80 automatically stopped as described.

The attendant, upon the conclusion of the cut, will remove the blank from the stopped work-spindle. Upon lifting the lever *a* and clutching the then-idling gear *Q*⁵ to the then-still shaft *F*⁶, the cutter-head will rise quickly to its initial position until arrested by the push of the projection *H*' against the collar *T*². The attendant can then mount a fresh blank on the then-still work-spindle. 95 Upon depressing the handle *a*, the hob will be moved quickly towards and stopped (by the cam *D*) near the upper end of the blank. The lever *B* is then operated to close the master-clutch and the handle *k* is then actuated to engage the clutch teeth *r*' and the correlation of ratios essential to the helical effect is thereby established, and the hob thereupon proceeds to enter the blank and cut the helix. 105

Without further analysis, the foregoing will so fully reveal the gist of this invention that others can, by applying current knowledge, readily adapt it for various utilizations by retaining one or more of the features that from the standpoint of the prior art, fairly constitute essential characteristics of either the generic or specific aspects of this invention, and, therefore, such adaptations should be, and are intended to be, comprehended within the meaning and range of equivalency of the following claims. 110

Having thus revealed this invention, I claim as new and desire to secure the following combinations and elements, or equivalents thereof, by Letters Patent of the United States:—

1. A balanced-drive hobbing-machine comprising a bed; a relatively heavy stanchion shiftably supported thereon; a work-supporting spindle non-shiftably journaled in said bed near one end thereof; an intermediate splined shaft and a parallel transmission shaft, each journaled on said bed transversely to said spindle; two pairs of 125 130

spur change-gears connecting said two shafts; a splined transmission shaft journaled on said stanchion parallel with said spindle; a head slideable on said stanchion; 5 a hob-supporting spindle on said head, said hob-spindle being inclined at a major angle of about a third to an eighth of a quadrant; means for effecting a minor adjustment of a few degrees of said major angle; two pairs 10 of angle-gears connecting said hob-spindle with said splined transmission shaft, one of said angle-gears being splined to said shaft; a pair of angle-gears connecting said shaft to said intermediate shaft, one of said gears 15 being splined to said intermediate shaft; and a pair of angle gears connecting said parallel transmission shaft with said non-shiftable work-spindle.

2. A balanced-drive hobbing-machine combining a bed; a work-supporting spindle occupying a fixed position on said bed; a heavy stanchion shiftably mounted on said bed; a hob-supporting spindle slidably carried by said stanchion, said spindle being set 25 at an angle restricted to about a third to an eighth of a quadrant; a transmission connecting said spindles and consisting of not more than one intermediate and two transmission shafts, said intermediate shaft being splined 30 and arranged parallel to the work-driving transmission shaft and transversely to the hob-driving transmission shaft; the adjacent ends of said two parallel shafts being directly connected by two pairs of change- 35 gears of the spur-tooth type, the hob-driving shaft being splined; an angle-gear slideable on said intermediate shaft; said hob-driving shaft being geared at one end to said spindle through four angle-gears and at its other end 40 geared directly to said slideable angle-gear, a prime-mover geared directly to the intermediate shaft whereby the power for driving said spindles will be derived from the respective ends thereof; and means for effecting a 45 progressive relative translation between said spindles in a direction parallel with the work-supporting spindle.

3. A hobbing-machine combining a hob-spindle; a work-spindle; a prime-mover; 50 a transmission having balanced six-gear branches, the one for driving the hob-spindle, and the other for driving the work-spindle; and means for mounting for said hob-spindle at a major angle of about a third to an eighth of a quadrant, said means providing a minor adjustment for increasing or decreasing said major angle within about five degrees.

4. A hobber for generating various helical gears having a common helix angle, said 60 hobber combining a hob-spindle; an angularly arranged mount for initially holding said hob-spindle at a base-angle corresponding to said common helix angle; means for enabling said mount to be swung through an

incidental angle sufficient to compensate for the helix angle of the hob carried by the hob-spindle; a work-spindle; and a transmission system for simultaneously rotating each of said spindles and translating said 70 hob spindle, said transmission system being ratioed to correlate said three component motions to generate a gear having the aforesaid common helix angle.

5. A hobbing-machine combining a hob-spindle; a work-spindle; a prime-mover; 75 a transmission having balanced six-gear branches, the one for driving the hob-spindle, and the other for driving the work-spindle; and means for mounting for said 80 hob-spindle at a definite major angle of about a third or an eighth of a quadrant, said means providing a restricted minor adjustment for increasing or decreasing said 85 major angle by a few degrees only.

6. A hobbing-machine combining a hob-spindle; a work-spindle; a prime-mover; 90 a transmission having balanced six-gear branches, the one for driving the hob-spindle, and the other for driving the work-spindle; means for mounting for said 95 hob-spindle at a definite major angle of about a third or an eighth of a quadrant, said means providing a restricted minor adjustment for increasing or decreasing said major angle by a few degrees only; a shiftable stanchion supporting said means; and a non-shiftable support for the work-spindle.

7. A hobbing-machine comprising a hob-spindle and a work-spindle; a transmission 100 having balanced branches for driving said respective spindles; restricted means for mounting said hob-spindle at a substantially fixed angle not greater than about a third or less than about an eighth of a quadrant; 105 a shiftable stanchion supporting said means; and a non-shiftable support for the work-spindle.

8. A helical-gear hobber combining a work-spindle; a hob-spindle set at a major 110 angle thereto representing the helix angle of the helical gear to be cut; a short shaft transverse to one end of the hob-spindle; a pair of angle gears directly connecting said shaft with said spindle; an elongated transmission shaft parallel with said work spindle; a second pair of angle-gears directly connecting said two shafts; and bearing means for said spindle, said means being angularly adjustable about said short shaft 115 as an axis, whereby said hob spindle may be swung through a small incidental angle to modify said major angle to the extent of compensating for the helix angle of the hob. 120

9. A helical-gear hobber combining a work-spindle; a hob-spindle at a major angle thereto representing the helix angle of the helical gear to be cut; a short shaft transverse to one end of the hob-spindle; a 125

worm and worm-wheel directly connecting said shaft with said spindle; an elongated transmission shaft parallel with said work spindle; a second pair of angle-gears directly connecting said two shafts; and bearing means for said spindle, said means having a sufficient range of angular adjustment about said short shaft as an axis, to enable said hob spindle with its worm-wheel to be 10 swung through a small incidental angle to compensate for the helix angle of the hob.

10. A hobbing machine adapted to generate helical-gears combining a work-spindle; a hob-spindle adapted to operate at a major angle thereto representing the helix angle of the helical gear to be cut; a worm-wheel affixed to one end of said spindle; a short shaft extending transversely from said end of the hob-spindle; a worm on 15 said shaft directly gearing it with said spindle; an elongated splined transmission shaft parallel with said work spindle; a second pair of angle-gears directly connecting said two shafts, one of said gears 20 being slidable on said splined shaft; angularly-adjustable bearing-means for enabling said spindle with its worm-wheel to be bodily swung about said short shaft as an axis through a small incidental angle 25 sufficient to compensate for the helix angle of the hob; a second transmission shaft; a pair of angle-gears connecting it to the work-spindle; an intermediate shaft; a pair 30 of angle-gears connecting it with said first transmission shaft; means for bodily translating the hob-spindle; and change-gears 35 between said intermediate shaft and said second transmission shaft for correlating the three component motions of the hob 40 and work spindles to produce the helical effect.

11. A hobber for generating helical-gears combining a work-spindle; a hob-spindle adapted to operate at a major angle thereto representing the helix angle of the helical gear to be cut; a first and a second worm-wheel affixed respectively to said spindles; a short shaft extending transverse from one end of the hob-spindle; a 45 worm affixed to said shaft in mesh with the worm-wheel on said hob-spindle for directly gearing said shaft to said spindle; angularly adjustable bearing-means for enabling said spindle with its worm-wheel to be bodily swung about said short shaft as an axis through a small incidental angle 50 to modify said major angle to the extent of compensating for the helix-angle of the hob; a balanced drive for relatively rotating said spindles through said worm-wheels; and means for feeding one of said spindles.

12. A hobber combining a work-spindle; a hob-spindle; a slidable head for one of 55 said spindles; a transmission for correlat-

ing the rotations of each spindle with the sliding relation therebetween to realize a predetermined helical effect; a prime-mover; a clutch; a hand-lever adapted to render said clutch effective to drive said 70 transmission; means for preventing said hand-lever from being manually actuated to discontinue said drive; a second hand-lever; and mechanism for enabling it to render said clutch ineffective. 75

13. A hobber combining a hob-spindle; a slidable head therefor; a work-spindle; a drive-system comprising a transmission extending from the one spindle to the other for establishing the rotational ratio there- 80 between; a branch transmission for sliding said head; a first means for positively relating said branch transmission to said spindle-driving transmission to correlate definitely the feed of the head with the 85 rotations of the spindles to realize the helical effect; a second means interchangeably available for more rapidly driving said branch transmission to cause a quick-traverse of said head; a control system for au- 90 tomatically rendering said second means impotent to traverse said head in the portion of its path utilized during the actual hobbing action.

14. A hobber combining a hob-spindle; a slidable head therefor; a work-spindle; a drive-system comprising a transmission extending from the one spindle to the other for establishing the rotational ratio there- 100 between; a branch transmission for sliding said head; positive means for relating said branch transmission to said spindle-driving transmission to correlate definitely the feed of the head with the rotations of the spindles to realize the helical effect; an im- 105 positive means interchangeably available for more rapidly driving said branch transmission to cause a quick-traverse of said head; a control system for automatically rendering said impositive means impotent 110 to traverse said head in the portion of its path utilized during the actual hobbing action; and an interlock for prohibiting the utilization of said positive means while said impositive means is potent. 115

15. A hobber combining a hob-spindle; a slidable head therefor; a work-spindle; a drive-system comprising a transmission extending from the one spindle to the other for establishing the rotational ratio there- 120 between; a branch transmission for sliding said head; a first means for positively relating said branch transmission to said spindle-driving transmission to correlate definitely the feed of the head with the 125 rotations of the spindles to realize the helical effect; a second means interchangeably available for more rapidly driving said branch transmission to cause a quick-traverse of said head; an interlock control sys- 130

- tem for automatically rendering said first means impotent to feed said head when said second means is set in action, and for permitting said first means to be utilized when said second is out; and an independent trip mechanism for automatically disconnecting said transmission from the source of motion when said head has carried the hob through the blank.
16. A hobber combining a work-spindle; a hob-spindle; a slidable head for one of said spindles; a transmission for correlating the rotations of each spindle with the sliding relation therebetween to realize a predetermined helical effect; a prime-mover; a clutch; a hand-lever adapted to render said clutch effective to drive said transmission; a latch for preventing said hand-lever from being manually actuated to discontinue said drive; a second hand-lever; and mechanism for enabling it to release said latch and render said clutch ineffective.
17. A hobber combining a work-spindle; a hob-spindle; a slidable head for one of said spindles; a transmission for correlating the rotations of each spindle with the sliding relation therebetween to realize a predetermined helical effect; a prime-mover; a clutch; resilient means urging said clutch open; a lever adapted to be operated manually to overcome said resilient means to render said clutch effective to drive said transmission; latch means for preventing said hand-lever from swinging reversely to discontinue said drive; a second hand-lever; and mechanism for enabling it to render said latch means ineffective and thereby permit said resilient means to open said clutch.
18. A hobber combining a work-spindle; a hob-spindle; a slidable head for one of said spindles; a transmission for correlating the rotations of each spindle with the sliding relation therebetween to realize a predetermined helical effect; a prime-mover; a clutch; resilient means urging said clutch open; a latch-device for holding said means in a position such that said clutch is closed; and a trip mechanism operated by said slidable head for releasing said latch-device to permit said means to open said clutch.
19. A hobber combining a hob-spindle; a slidable head therefor; a work-spindle; a transmission extending from the one spindle to the other for establishing the rotational ratio therebetween; a prime-mover; a clutch for connecting it to said transmission; a branch transmission for sliding said head; a first means for positively relating said branch transmission to said spindle-driving transmission to correlate definitely the feed of the head with the rotations of the spindles to realize the helical effect; a second means interchangeably available for more rapidly driving said branch transmission to cause a quick-traverse of said head; an interlock control system for automatically rendering said first means impotent to feed said head when said second means is set in action, and for permitting said first means to be utilized when said second is out; a first trip mechanism for rendering said second means ineffective before said branch transmission has carried said head into the hobbing region; and an independent trip mechanism for automatically disconnecting said clutch when said head has carried the hob through the blank.
20. A hobber combining a hob-spindle; a slidable head therefor; a work-spindle; a drive-system comprising a transmission extending from the one spindle to the other for establishing the rotational ratio therebetween; a prime-mover; a first clutch for connecting it with said drive-system; a branch transmission for sliding said head; a second clutch for positively relating said branch transmission to said drive-system to correlate definitely the feed of the head with the rotations of the spindles to realize the helical effect; a reversing clutch; means continuously driven by said prime-mover adapted to be connected through said third clutch with said branch transmission to cause a quick-traverse of said head; a trip mechanism operated by said slidable head for so controlling said reversing clutch that it can cause the head to descend only when the hob is out of contact with the blank, said trip mechanism being adapted to open said first clutch at the conclusion of the hobbing operation; and an interlock for opening said second clutch whenever said reversing clutch is closed.
21. A helical-gear hobber combining a rotatable hob-spindle; a rotatable work-spindle; a feedable head for one of said spindles; a general transmission positively actuating said parts simultaneously at rates correlated to yield a helical effect; a prime-mover; a master friction-clutch; means operable either automatically by said head or manually for opening said friction-clutch; and a hand-lever for closing said friction-clutch to cause said prime-mover impositively to drive said general transmission.
22. A helical-gear hobber combining a rotatable hob-spindle; a rotatable work-spindle; a feedable head for one of said spindles; a general transmission positively actuating said parts simultaneously at rates correlated to yield a helical effect; a prime-mover; a master friction-clutch; two hand-levers, the first for closing and the second for opening said friction-clutch; and a connection for enabling said feedable head at a predetermined station to operate said second lever automatically.
23. A helical-gear hobber combining a hob-spindle; a work-spindle; a normally

idling but continuously-driven transmission terminating in a reversing mechanism; a general transmission for relatively rotating and feeding the spindles at rates correlated to produce a helical effect; a positive-clutch in said general transmission for discontinuing the feeding action thereof; a prime-mover; a friction-clutch; a hand-lever for closing said friction clutch to connect said prime-mover with said general transmission; another lever operable manually and automatically to disconnect said friction-clutch; and a third-lever adapted first to open said positive-clutch and then to render said reversing-mechanism operable to transmit motion from said continuously-driven mechanism in either direction.

24. A helical-gear hobber combining a pair of spindles; a feedable-head for one of said spindles; a transmission extending continuously from the one to the other for permanently maintaining the rotational ratio predetermined by a preliminary setting, and having a branch-transmission leading to said head; a positive-clutch for isolating said branch-transmission from said first transmission; a fast-running transmission; a motion-reverser for disconnecting or connecting the latter with the branch-line transmission; a lever shiftable to occupy either one of three positions to control said motion-reverser; a second lever for controlling said positive-clutch; a master friction-clutch; a third lever for closing said master friction-clutch; a fourth lever for opening said friction-clutch; and mechanism adapted to be actuated by said feedable head for operating said fourth lever automatically.

25. A helical gear hobber combining a work-spindle; a hob-spindle; a mounting constructed to support said hob-spindle at a major angle corresponding to the helix angle of the gear to be cut, but tilttable sufficiently to afford an incidental angular adjustment of the hob spindle to compensate for the helical angle of the hob cutter; a splined shaft arranged transversely to the hob

spindle and parallel to the work spindle; gears connecting said splined shaft and hob spindle and adaptable to said extent of adjustment; a prime mover geared to said splined shaft; a transmission shaft geared to said work spindle; means to translate said hob spindle bodily parallel with said work spindle; and change gears between said prime mover and transmission shaft for correlating the three component motions of said hob and work spindle to produce a gear whose helical angle corresponds with the major angle of the hob spindle.

26. A helical hobber combining a continuously running prime-mover; a main transmission system; a master-clutch therebetween; work and hob spindles adapted to be co-relatively rotated and translated by said system; an auxiliary transmission continuously driven by said prime-mover independently of said master-clutch; and control means enabling said auxiliary transmission to accomplish a rapid relative translation between said spindles when said main transmission system is ineffective to effect its translation between said spindles.

27. A helical hobber combining two spindles rotatable and translatable relatively; means connectable therewith for accomplishing said translation rapidly; a lever adapted when moved in a given direction so to connect said means as to enable it to translate one of said spindles rapidly in said direction; a trip for automatically disengaging said means at a predetermined station in the advance of said translation; means connectable for slowly continuing said translation; manual means for reversing the direction of said translation; and an interlock for substituting said first-mentioned for said second-mentioned means when said reversing means has been resorted to.

In witness whereof, I have hereunto subscribed my name.

WILLIAM F. ZIMMERMANN.
